UNITED STATES PATENT OFFICE.

ELUE O. FRITCH, OF BELMONT, MASSACHUSETTS, ASSIGNEE TO HOOD RUBBER COMPANY, OF WATERTOWN, MASSACHUSETTS, A CORPORATION OF MASSACHUSETTS.

DESIGN FOR A TIRE.

Application filed March 2, 1922. Serial No. 978. Term of patent 14 years.

To all whom it may concern:

Be it known that I, ELUE O. FRITCH, a citizen of the United States, residing at Belmont, Massachusetts, have invented a new, original, and ornamental Design for Tires, of which the following is a specification, reference being had to the accompanying drawing, forming a part hereof.

Fig. 1 is a plan view of a portion of a tire showing my new design, and

Fig. 2 a transverse section as viewed along the line 2—2 of Fig. 3.

Fig. 3 is a side elevation.

I claim:

The ornamental design for a tire, as shown.

ELUE O. FRITCH.
